US0D1105226S

(12) **United States Design Patent** (10) Patent No.: **US D1,105,226 S**
(45) Date of Patent: ** Dec. 9, 2025

(54) **SELF-SERVICE PAYMENT TERMINAL**

(71) Applicant: **PAX COMPUTER TECHNOLOGY (SHENZHEN) CO., LTD.**, Shenzhen (CN)

(72) Inventors: **Yuzhuo Wang**, Shenzhen (CN); **Shuxian Shi**, Shenzhen (CN); **Sheng Chen**, Shenzhen (CN)

(73) Assignee: **PAX COMPUTER TECHNOLOGY (SHENZHEN) CO., LTD.**, Shenzhen (CN)

(**) Term: **15 Years**

(21) Appl. No.: **29/967,672**

(22) Filed: **Oct. 11, 2024**

(30) **Foreign Application Priority Data**

Sep. 6, 2024 (CN) 202430570879.8

(51) LOC (15) Cl. **18-01**

(57) **CLAIM**

The ornamental design for a self-service payment terminal as shown and described.

DESCRIPTION

FIG. 1 is a bottom, front, right side perspective view of a self-service payment terminal;

FIG. 2 is a top, rear, left side perspective view thereof;

FIG. 3 is a front view thereof;

FIG. 4 is a rear side view thereof;

FIG. 5 is a left side view thereof;

FIG. 6 is a right view thereof;

FIG. 7 is a top view thereof; and,

FIG. 8 is a bottom view thereof.

The broken lines in the drawings depict portions of the self-service payment terminal that form no part of the claimed design.

1 Claim, 8 Drawing Sheets
